DALLAS F. GRAHAME, OF WESTMOUNT, QUEBEC, CANADA, ASSIGNOR TO RILEY STOKER CORPORATION, OF WORCESTER, MASSACHUSETTS, A CORPORATION OF MASSACHUSETTS

RECIPROCATING MECHANISM

Application filed September 24, 1924. Serial No. 739,701.

My invention relates to reciprocating mechanisms and more particularly to a mechanically operated mechanism for reciprocating the ram of a stoker or any other element which is to be moved in alternate directions at a uniform rate.

Coal is ordinarily fed into the combustion chamber of a stoker by means of a ram which is reciprocated past the opening of a coal hopper in such a manner as to force the coal intermittently into the furnace. This ram is ordinarily operated by means of a crank driven by a worm gear mechanism. This type of drive, as heretofore constructed, has resulted in a large loss of power due not only to the low efficiency of the driving mechanism but particularly to the fact that considerable friction is generated by the lateral pressure of the crank arm on the ram. It is not possible to lubricate the ram owing to the presence of coal dust, hence any lateral pressure is highly objectionable because of the friction losses as well as the wear on the ram and its casing.

It is the main object of my invention to overcome these difficulties and to provide a simplified construction for a reciprocating mechanism which may be easily built and quickly assembled and which will have a relatively high efficiency.

It is a further object of my invention to provide a mechanical movement for reciprocating bodies of various types which is so constructed that a rotary uni-directional motion may be efficiently converted into a linear reciprocatory motion.

It is a further object of my invention to provide a stoker ram driving mechanism which will give a longitudinal straight thrust upon the ram and thus eliminate lateral pressure and high frictional losses and which is so constructed that if a battery of stoker rams is employed any individual ram may be separately controlled irrespective of the operation of the other rams.

With these and other objects in view as will be apparent in the following disclosure, my invention resides in the combination of parts set forth in the specification and covered by the claims appended hereto.

Referring to the drawings, in which like

reference numerals indicate like parts, I have there illustrated one embodiment of my invention as applied to a stoker in which:

Fig. 1 is a vertical section through the center of the reciprocating mechanism;

Fig. 2 is an end elevation with parts in section to show details of the construction;

Fig. 3 is an enlarged sectional detail showing the manner of connecting the worm to its supporting key shaft;

Fig. 4 is an end elevation showing a plurality of stoker rams driven from a common driving shaft; and

Fig. 5 is an enlarged view partly in section showing the arrangement of the ram, its driving mechanism and the stoker.

The application of a mechanically operated reciprocating mechanism embodying my invention to one type of stoker is illustrated in the drawings, in which the reciprocating mechanism 10 is directly connected to the stoker ram 11 which is reciprocable in the casting 12 beneath and past the throat of the hopper 13 through which coal is fed into the furnace. This coal is passed through an opening 14 in the front wall 14 of the furnace into the retort 15 of the stoker.

In accordance with my invention, I propose to convert a rotary motion into a reciprocatory linear one by employing a screw and a nut which are so constructed and arranged that the screw may be held from rotation and moved longitudinally by rotation of the nut, or it may be moved in the opposite direction by rotating the screw relative to the nut.

This reverse movement of the screw may be caused by rotating the screw in the same direction as the nut but at a higher rate. An automatically operated clutch mechanism may be employed to hold the screw stationary at one time and to cause its rotation at another time, whereby the reciprocatory motion of the screw is insured.

The embodiment illustrated in the drawings comprises a hollow worm 20 which has at one end a reduced portion 21 carrying flanges 22 arranged to form with the member 23 a thrust bearing which permits rotation of the worm. The bearing member 23 is connected to the ram 11 by means of the pin 24. The

worm is slidably keyed to the key shaft 25 mounted within the worm by means of a set of keys 26 which are slidable in their key ways on the shaft as well as the inner wall of the worm. These keys are prevented from longitudinal movement but are permitted to rotate by providing them with upturned lugs 27 rotatably mounted in an internal annular groove of the collar 28 which is fixed to the end of the casing 29. This construction permits the worm and the key shaft to rotate as well as to move longitudinally.

Threaded onto the worm is an elongated nut 30 which may be made in several parts but is shown as an integral member for the sake of clearness of illustration. This nut 30 has a reduced end portion 31 rotatably mounted in the hub 32 which is supported from an inner wall of the casing 29. The other end of the nut has a reduced portion 34 which is likewise mounted within a radial bearing 35 fixed to the casing wall. Ball bearings 36 may be employed to take up the end thrust on the nut.

25 The nut is adapted to be rotated in one direction by means of a gear 40 which is fixed to the nut and here shown as integral therewith. This gear 40 is driven by a worm 41 which in turn is rotated by a sprocket 42 driven from a chain 43 connected to a motor or other suitable driving mechanism. As illustrated in Figs. 2 and 4, this driving worm 41 may be suitably mounted in radial and thrust bearings and connected to the worms of other driving mechanism in alignment therewith by a flexible coupling 44 of suitable construction.

A further gear 46 (Fig. 1) formed on the outside of the nut 30 meshes with a gear 47 keyed to the short shaft 48 which is suitably mounted on the casing. A further gear 49 connected to the gear 47 in turn meshes with a gear 50 which is mounted on the nut 30 to rotate relative thereto. A thrust member 51 is integrally fixed to the casing wall and so arranged as to prevent the gear 50 from moving laterally in its bearing. These various gears are of such shape and size that the gear 50 will rotate faster than the gear 40 and in the present embodiment at twice the speed, so that the forward and reverse motions of the worm may be at the same speed.

In order to hold the worm from rotation at one time and permit it to rotate at another, 55 I provide a clutch mechanism which comprises a stationary member 54 mounted concentric with the key shaft 25. A movable clutch member 56 is keyed to the shaft 25 and mounted within the member 54. The stationary member 54 and the movable clutch member 56 are provided with clutch teeth 57 arranged to be brought into mesh. The opposite side of the movable clutch member 56 is provided with teeth 59 which are arranged 60 to mesh with teeth 59 projecting from the

side of the gear 50. Springs 60 and 61 are provided on opposite sides of the shiftable clutch member to aid in shifting the same.

It will now be seen that when the clutch member 56 is in the position illustrated in Fig. 1, the key shaft 25, which is slidably keyed to the clutch member 56, is prevented from rotating. The worm 20 slidably keyed to shaft 25 is likewise prevented from rotation, and as the nut 30 is driven by the sprocket 42 rotating in the direction illustrated by the arrow *a* in Fig. 1, the worm 20 and therefore the ram 11 are caused to move laterally in the direction of the arrow *b*. If now the clutch is thrown to connect the teeth 58 and 59, the key shaft and therefore the worm will be connected to the gear 50 which rotates at twice the speed of nut 30. The worm will then be caused to rotate in the same direction as the nut but at a much faster speed, and it will accordingly be drawn backward through the nut so as to reverse the direction of the ram and return it to its original position.

In order that this reversal of motion may be caused automatically, I provide the inner portion of the worm 20 with a shoulder 65 (Fig. 3) which is arranged to contact with an enlargement 66 on the end of the key shaft 25 when the worm has reached the desired outward limit of motion. This serves to move inwardly the collar 67 which is pinned to the key shaft and thereby compress the spring 61 which in turn pushes against the clutch member 56 and disconnects the clutch teeth 57, thereby throwing the clutch member to reverse the movement of the worm. At this time the worm 20 is at its outward limit of travel and the spring 60 is accordingly free to move without being compressed, hence the teeth 58 and 59 will remain in contact until the worm has been again brought inwardly into contact with spring 60, whereupon this spring will be compressed and thrust the clutch member 56 in the opposite direction.

The forces involved in operating the stoker are enormous and at times an obstruction within the stoker may endanger the mechanism, hence I provide a safety feature which permits the worm to stand still if an obstruction is met when the worm is travelling outwardly and the stoker ram is pushing fuel into the furnace. To this end, I so construct the parts that the stationary clutch member 54 may rotate if the pressure thereagainst is above a certain maximum, and thus permit the worm to rotate freely with the nut. This may be accomplished as illustrated by mounting the member 54 rotatably on the collar 67 and clutch member 56 which are concentric with the key shaft, and prevent end movement of the member 54 by means of a yoke 75 on the clutch member which is held by an adjustable pin 76 mounted on a lug on the end of the casing 29.

The member 54 is also provided with a single tooth 78 (Figs. 1 and 2) which is normally held by a tooth 79 on a sleeve 80. This sleeve is pinned to the bar 81 which is in turn rotatably mounted in suitable bearings in the top of the casing. A collar 84 fastened on the rod 81 outside of the casing is normally pinned in place by a shearing pin 85 which is made of such size and material that if too great a pressure is placed on it it will shear off. When the pressure of tooth 78 on the tooth 79 is excessive, the pin 85 shears and the rod 81 and the member 80 slide longitudinally until the tooth 78 loses contact with tooth 79 and permits rotation of the normally stationary clutch member 54.

If it is desired to stop the operation of the reciprocating mechanism, as for instance when any particular retort has acquired more coal than the neighboring retort, then by turning the handle 87 on rod 81 through a sufficient arc, the clutch tooth 79 is released sideways from engagement with the tooth 78 and the clutch member 54 is permitted to revolve. In order to start the ram mechanism into operation it is merely necessary to push down on the handle 87 and bring the tooth 79 into the path of the tooth 78 and if the pin 85 is in place the member 54 will be held stationary and the worm also held during the inward travel of the ram into the furnace.

It will now be seen that I have provided a reversing and reciprocating mechanism of general utility which may be manually controlled to permit it to reciprocate continuously in accordance with a predetermined movement, or the parts may be stopped at will. The device is safe, owing to the presence of the shearing pin 85 and will not be broken if an obstruction is met by the ram or other body being moved. A mechanical movement of this kind is efficient and may be easily made and assembled as there are but few parts and these are of simple design. The reciprocating mechanism may be completely housed in a casing and suitably oiled and protected from dust. This mechanical movement permits a direct thrust upon the ram and no force is lost in lateral pressure upon the ram casing. Various other advantages will be apparent to one skilled in the art, and it is to be understood that this invention is not limited to the particular mechanism and construction illustrated in the drawings and herein described except as limited by the claims appended hereto.

In view of the above disclosure, it will be within the capabilities of one skilled in this art to rearrange the parts so that the nut will be connected to reciprocate the ram, and the claims are to be given this interpretation as covering such equivalent arrangements.

Having thus described my invention, what

I claim as new and desire to secure by Letters Patent is:

1. A reciprocating mechanism comprising a nut and a screw threaded therein, means to hold one part immovable longitudinally, means permitting the other part to move axially, means to rotate the longitudinally immovable part in one direction, means to rotate the axially movable part in the same direction at a higher rate of speed, a clutch effective to hold the axially movable part rotatably stationary or permit rotation thereof, and means operated by the axially movable part effective to throw the clutch and thus cause said part to reciprocate.

2. A reciprocating mechanism comprising a nut and a screw threaded therein, means to hold one part immovable longitudinally, means permitting the other part to move axially, means to rotate the longitudinally immovable part in one direction, means to rotate the axially movable part in the same direction at a higher rate of speed, a clutch effective to hold the axially movable part rotatably stationary or permit rotation thereof, means operated by the axially movable part effective to throw the clutch and thus cause said part to reciprocate, and manually controlled means effective to stop the reciprocation of said part.

3. A reciprocating mechanism comprising a nut and a screw threaded therein, means to hold one part immovable longitudinally while permitting rotation thereof, means permitting the other part to move axially, means to rotate the nut and the screw in the same direction, one at a higher rate than the other, and means effective to prevent rotation of the faster rotating part at intervals and thus cause reciprocation of the axially movable part.

4. A reciprocating mechanism comprising a longitudinally movable worm, a rotatable longitudinally immovable nut therefor, means to rotate the nut, means to rotate the worm in the same direction at a faster rate, and means effective to permit rotation of the worm or hold it rotatably stationary and thereby cause reciprocating motion thereof relative to the rotated nut.

5. A reciprocating mechanism comprising a rotatable longitudinally immovable nut, a worm threaded therein and mounted for rotative and longitudinal movement, means to rotate the nut in one direction, means to rotate the worm in the same direction at a higher rate of speed, a clutch effective to permit rotation of the worm or to hold the worm stationary, and means operated by movement of the worm effective to throw the clutch to permit continuous reciprocation of the worm.

6. A reciprocating mechanism comprising a nut, a worm threaded therein, one part being longitudinally and rotatably movable relative to the other, means to rotate both

- parts at different speeds, a clutch mechanism effective to prevent or permit rotation of the longitudinally movable part, and manually-controlled means to permit both parts to rotate at the same speed and prevent relative longitudinal movement thereof.
7. A reciprocating mechanism comprising a rotatable nut, a longitudinally movable and rotatable worm threaded within the nut, means to rotate the nut in one direction and the worm in the same direction at a higher rate of speed, a clutch mechanism effective to prevent rotation of the worm or permit rotation thereof, means operated by movement of the worm effective to throw the clutch and permit reciprocation of the worm, and manually controlled means to render the clutch inoperative and permit the worm to rotate with the nut and be longitudinally immovable.
- 10 8. A reciprocating mechanism comprising a nut and a worm threaded therein for relative rotative and longitudinal movement, means to hold one of said members longitudinally immovable, means to rotate the nut, means to rotate the worm to cause longitudinal movement of one member, means to prevent rotation of the longitudinally movable member at stated intervals while the other rotates and cause movement of the worm through the nut, and means effective, if the end thrust of the longitudinally movable member is excessive, to permit rotation thereof with the other and prevent further endwise movement.
- 15 9. A reciprocating mechanism comprising a rotatable nut, a worm threaded therein for rotative and longitudinal movement, means to rotate the nut, means to rotate the worm at a different rate, means to prevent rotation of the worm at stated intervals and cause longitudinal movement thereof through the rotating nut, and means effective if the end thrust of the worm is too great to permit rotation thereof with the nut and prevent further endwise movement.
- 20 40 10. A reciprocating mechanism comprising a reciprocable ram, a longitudinally movable rotatable worm connected to said ram and arranged to push directly thereagainst in the direction of movement of the ram, a rotatable longitudinally immovable nut mounted on said worm, means to rotate the nut in one direction, means to rotate the worm in the same direction at a rate higher than that of the nut, and means effective to hold the worm rotatably stationary and cause longitudinal movement of the ram or permit rotation of the worm and cause the ram to move in the opposite direction.
- 25 30 35 45 50 55 60 65
- Signed at Worcester, Massachusetts, this 12th day of September, 1924.

DALLAS F. GRAHAME.
